UNITED STATES PATENT OFFICE.

ELHANAN L. MOODIE, OF NEW YORK, N. Y., ASSIGNOR TO GILLESPIE
& MOODIE, OF SAME PLACE.

DESIGN FOR AN EASEL.

SPECIFICATION forming part of Design No. 12,745, dated February 7, 1882.

Application filed November 19, 1881. Term of patent 3½ years.

To all whom it may concern:

Be it known that I, ELHANAN L. MOODIE, a citizen of the United States, residing in the city and county of New York, in the State of New York, have invented and produced a new and original Design for Advertising or Ornamental Easels, of which the following is a specification, reference being had to the accompanying drawings, forming a part thereof.

Figure 1 is a front view, and Fig. 2 an edge view, these two views being deemed necessary to fully illustrate my said design.

The leading feature of my design consists in a novel configuration and graphic representation of the plate or face of an "easel," so termed, designed for ornamental or advertising purposes, the same comprising the representation of a sunflower upon the front of the said face or plate, and in a scalloped circumferential edge substantially corresponding to the contour of a sunflower as ordinarily conventionalized. Thus, for example, at the center A is a circular disk-like representation of the core or seed portion of a sunflower, and surrounding the same an outer portion, B, of leaf-like figures radiating from the center portion, A, and with their pointed outer ends alternating to produce the scalloped configuration herein-

before referred to, the material of which the said plate or face is made being cut coincident with the points of the leaf-like figures to give the said material the scalloped circumference corresponding to the scalloped circumference of the entire figure. The scalloped circumference, in connection with the leaf-like figures, and the central portion, representing the seed portion of a sunflower, cause the plate or face aforesaid to present to the eye a vivid and pleasing representation of a sunflower. The surface of said face or plate may be appropriately colored in tints corresponding to those of the corresponding portions of the true sunflower.

What I claim as my invention is—

The design for an advertising or ornamental easel herein shown and described, the same having a scalloped circumferential edge and composed of the parts A B, representing respectively the central or seed portion and the leaves or petals of a sunflower, substantially as described.

ELHANAN L. MOODIE.
